UNITED STATES PATENT OFFICE

CHARLES A. HUFF, OF PHILADELPHIA, PENNSYLVANIA

CLIPPING DEVICE

Application filed November 14, 1927. Serial No. 233,034.

This invention relates to apparatus for shearing metal projections and more particularly to a device for clipping the ends of bolts.

The object of the invention is to provide a tool, of simple and rugged construction, adapted to be quickly manipulated, and capable of operating in a confined or limited space otherwise inaccessible or difficult to reach.

A feature of the invention resides in the provision of a plurality of cutters whose upper faces incline at slight angles to a horizontal plane, in combination with a pressure element whose axis intersects the planes of said faces and is parallel to the horizontal plane.

Another feature of the invention comprises the arrangement of a jaw fixed within a guideway, and a jaw movable on a second guideway responsive to the actuation of a pressure element, said guideways being transverse to each other. The first jaw is adapted to be removed from its guideway, the second jaw then being removable.

A further feature covers the structure of the cutters whereby a bolt may be clipped directly at the surface from which it protrudes notwithstanding that the bolt, at said point in the surface, is substantially inaccessible from in front, but accessible from the side.

Other objects and features will be apparent from the following description of the invention read in conjunction with the accompanying drawings in which,

Figure 1 is a plan view of a device incorporating the invention.

Figure 2 is a side view thereof, showing the formation of the jaws and the relation with respect to an imaginary surface when in position for cutting a bolt, or the like, projecting through the surface.

Figure 3 is a cross-section of the device illustrating its mode of operation.

Figure 4 is a perspective view of one of the cutters, and

Figure 5 shows a section through line 5—5 of Figure 2, illustrating the assembly of the movable cutter on the base of the device.

Considering all the figures simultaneously, similar designations referring to similar parts, numeral 6 represents the base of the device. Mounting 7 is an integral part of the

base in which threaded arm 8 is positioned and through which it travels responsive to rotation of the knurled handle 9 by hand, or by a wrench applied to square end 10. A guide or key 11 preferably dove tailed in cross-section is integrally formed longitudinally of the base and provides a mounting for a cutting jaw 12, the cutting jaw having a keyway therein on its under side shaped to slidably fit upon the guide 11.

A second cutting jaw 13 is provided adapted to cooperate with the jaw 12, the bottom portion of which is shaped with a projecting portion as clearly shown in Figures 3 and 4 of the drawings, adapted to fit within a guideway or groove 14 provided in the base of the device and extending transversely of the entire width of the base. This guideway is provided with an undercut recess to accommodate the projection on the base of the cutting jaw snugly fitting therein adapting the jaw for sliding adjustment transversely of the base in the assembly of the parts. The jaw is fixed in position by a bolt or screw 13^a passing therethrough and threaded to the head of the base.

To assemble the device, jaw 12 is slid upon guide 11 whereupon jaw 13 is fixed within guideway 14.

The outer face 16 of jaw 13 is inclined at an angle, preferably about 8° to the horizontal. In the drawings, the bottom of base 6 is illustrated as horizontal and the upper face 16 is shown as inclined 8° thereto. Upper face 17 of jaw 12 is also inclined but at a lesser degree. In other words, the outer surface of faces 16 and 17 of the jaws are inclined to each other at an angle of approximately 8°. The object of inclining the faces is to enable square end 10 to be turned by a socket wrench, or the like, when it is desired to use the tool in close quarters flush against the surface from which a protruding element is to be clipped and the cutting portions of these jaws project beyond a plane passing through the two farthest extensions of the supporting base 6 in the general direction of the jaws.

It is evident that if dot and dash line 18 of Figure 2 represents a surface, the application of the tool, as illustrated, for the purpose of shearing a projection therefrom will leave

square end 10 at a distance from the surface sufficient for its actuation by a wrench. If the faces of the teeth were horizontal, end 10 could not be reached unless arm 8 were lower on the mounting and the tool redesigned.

5 With the present combination, the rugged qualities of the device may be retained and a saving effected in material and size due to the inclination of the body faces.

10 Figure 3 illustrates the tool in use. Bolt 19 projecting beyond surface 20 will be sheared off upon the application of force to the arm at end 10. The device is first applied to the bolt by loosening the arm and placing the 15 jaws adjacent the bolt, adjusting the arm by hand until the position shown in Figure 3 is attained. A wrench may then be applied to end 10 and the bolt sheared off.

Inasmuch as jaw 13 is mounted transverse 20 to jaw 12, and since guide 11 is transverse to guideway 14, the strain on the base of the tool will not be unduly applied at one point or along any one line mentioned. Also due to the use of guideways as disclosed, the possibility 25 of the parts becoming loose is reduced to a minimum. If desired, faces of jaws 12 and 13 may be reduced in width at cutting edges 21, as illustrated in Figure 1.

While the drawings illustrate one form of 30 the invention, it is evident that various modifications may be designed in which a pair of jaws may be utilized in combination with keyways transversely positioned to each other. Applicant limits himself to no form of jaws, 35 keyways or pressure element in combination with his cutting means. Any arrangement in which a pair of jaws movable at an angle to each other, and having beveled faces whereby an arm in alignment therewith is positioned 40 away from the surface to which the cutters are applied, is deemed within the purview of applicant's invention.

What is claimed is:—

1. A tool for cutting projections from a surface comprising a base, a pair of jaws mounted 45 on the base, a pressure element for moving said jaws together, the outer faces of said jaws having an upwardly converging slope to a point beyond one side of the base, whereupon the pressure element will be positioned sufficiently 50 from the surface to permit gripping thereof by a wrench.

2. A clipping tool comprising a pair of cutting jaws, each jaw having a face forming one 55 side of an acute angle constituting a cutting edge, planes through said faces being slightly inclined to each other and to a horizontal plane, a pressure element for bringing the jaws in cutting contact, the axis of said element being horizontal.

3. A tool for clipping metal comprising a base having a guideway, a mounting on the base, an arm positioned within and threaded 60 through the mounting, a cutter slidable in the guideway, means for fixing said cutter in the

guideway, a second cutter slidable transversely to the first and actuated responsive to the movement of said arm to contact with the first cutter, means on the arm for gripping it by hand, means for applying a wrench thereto, said cutters being arranged so that upon their application to a surface in substantially flush relation therewith, the face of the fixed cutter shall be at an angle to the horizontal a trifle greater than the angle of the second cutter, the axis of said arm being horizontal and forming an acute angle with a plane through either face of said cutters.

4. A tool for cutting projections from a surface comprising a base, cutting jaws mounted on the base, a pressure element for actuating one of said jaws, the outer faces of the jaws extending beyond the other parts of the tool and sloping toward each other at slight angles to a plane passing through the two farthest extensions of portions of the base in the same direction in which the jaws extend from said base.

5. A clipping device including a base having a recess in one side thereof, a fixed and a movable jaw in said recess having portions thereof projecting beyond the recessed side, the outer surface of the projecting portions of one of the jaws being sloped from the plane of the corresponding surface of the other jaw.

6. A clipping device including a base, a stationary and a movable jaw on said base, the outer surface of one of said jaws being inclined to the plane of the outer surface of the other jaw.

7. A clipping device including a base having spaced abutments extending in the same plane and in the same direction from the base, a fixed and slidable jaw between said abutments having their outer surfaces inclined outwardly at a slight angle beyond a plane passing through the outer extremities of said abutments.

In testimony whereof I have signed my name to this specification.

CHARLES A. HUFF.
